Atty's:

UNITED STATES PATENT OFFICE.

JOHN A. FISHER, OF CHICAGO, ILLINOIS, ASSIGNOR TO IMPERIAL PLAYER ROLL COMPANY, OF CHICAGO, ILLINOIS, A CORPORATION OF ILLINOIS.

MUSIC ROLL AND APPARATUS FOR MAKING SAME.

Application filed April 19, 1920. Serial No. 374,824.

To all whom it may concern:

Be it known that I, JOHN A. FISHER, a subject of the King of Great Britain, residing at Chicago, in the county of Cook and 5 State of Illinois, have invented new and useful Improvements in Music Rolls and Apparatus for Making Same, of which the following is a full, clear, concise, and exact description, reference being had to the accompanying drawing, forming a part of this 10 specification.

My invention relates to music-rolls and apparatus for making same.

One of the objects of my invention is to 15 provide an improved tab for a note-sheet.

Other objects of my invention are to provide improved apparatus for securing the tab to the note-sheet; improved means for producing an impression on the note-sheet; 20 and improved means for simultaneously securing the tab to the note-sheet and making an impression on the note-sheet.

Further objects will appear from the detailed description to follow and from the 25 appended claims.

In the drawings, in which an embodiment 30 of my invention is shown, Figure 1 is a side elevation of a machine for securing a tab to a note-sheet and printing a title and other indicia on the note-sheet;

Fig. 2 is an enlarged, vertical, sectional view of parts of the machine shown in Fig. 1;

Fig. 3 is a plan view of the movable note-sheet carriage and associated parts;

Fig. 4 is a view of a part of the machine shown in Fig. 1;

Fig. 5 is a view of the blank for a tab;

Fig. 6 is a view, showing the tab in condition to be secured to the front end of the 40 note-sheet; and

Fig. 7 is a sectional view, on an enlarged scale, of the tab, on the line 7—7 of Figure 6, when secured to the note-sheet.

In order to give a general idea of my 45 invention before describing in detail its specific embodiment, I will state that note-sheets for automatic musical instruments now in use usually have a tab secured to the front end thereof for attachment to the take-up 50 spool, and that it is customary to provide the front end-part of the note-sheet with a label; which label may give the name of the manufacturer, the name of the musical selection, and any other desired indicia. In using the

apparatus shown, the operator places the 55 note-sheet on a movable carriage, places a moistened, adhesive tab in proper position with respect to the front end of the note-sheet, and then presses a handle to swing the movable carriage about its axis. This movement of the movable carriage about its axis 60 brings the note-sheet against a stationary type-block, which prints the title and other desired indicia on the note-sheet and causes a presser-member to force the moistened, adhesive tab firmly against the note-sheet to 65 secure it thereto.

Referring now to the drawings in detail, and first to the tab which is secured to the front end of the note-sheet (shown in detail 70 in Figs. 5, 6 and 7), the blank for this tab comprises three portions,—a triangular portion 10, an annular portion 11, and a tongue or connecting portion 12 between the portions 10 and 11. This blank may be of any 75 suitable, flexible fabric and has one face entirely covered with an adhesive.

When the tab is to be secured to the front end of the note-sheet 13, the operator moistens the adhesive face of the tab, inserts 80 the annular portion 11 through the metal ring 14, bends the tongue-portion 12 and the annular portion 11 into the position shown in Fig. 6, probably pressing the annular portion 11 against the triangular portion 10, 85 places the triangular portion 10 in proper position with respect to the front end of the note-sheet, with the moistened, adhesive face of the triangular portion in contact with the note-sheet, and then operates the machine 90 to cause the tab to be pressed firmly against the note-sheet.

The following facts will be noted: That both portions 10 and 11 of the tab are 95 located on the same side of the note-sheet when the tab is secured thereto; also, that the triangular portion 10 of the tab has two separated areas secured by the adhesive to the note-sheet—that is to say, it has a circular portion, inside the annular portion 100 11, secured to the note-sheet through the opening in the annular portion 11 (Fig. 7), and it also has the portion, outside of the annular portion 11, secured to the note-sheet; further, that the annular portion 11, itself, 105 will be caused to adhere to the triangular portion 10, due to the adhesive between the two; and finally, that there is a double thick-

ness of the tab overlying, and secured to, the note-sheet. The double thickness of the tab makes the construction more durable and the tab less liable to break or crack at the 5 tongue-portion 12 thereof than would be the case if only one thickness of the fabric were used, and the fact that both thicknesses of the fabric are designed to lie upon one face of the note-sheet facilitates the securing 10 of the tab thereto. The opening of the annular portion 11 permits the triangular portion 10 to be secured directly to the note-sheet adjacent the extreme front end thereof, resulting in a much stronger connection 15 than would be the case if the opening were not there. If that part of the tab overlying the triangular portion 10 (Fig. 6) were carried back without exposing the intervening adhesive surface, it would result that a 20 considerable area of the triangular portion 10 could not be caused to adhere to the note-sheet, and the tab would be liable to become separated therefrom.

The placing of both portions 10 and 11 on 25 the same side of the note-sheet facilitates the use of the apparatus for mechanically pressing the tab against the note-sheet to secure it in place.

I will now describe the apparatus for 30 securing the tab to the note-sheet and printing the title and other desired indicia. This machine comprises, in general, a stationary bed or platen 15, on which the type-block 16 is supported, and a movable jaw or carriage 17, which carries the note-sheet up against the type-block 16. A pivoted presser-member 18 is mounted on the movable carriage 17 to move therewith, this presser-member 18 being brought into engagement 35 with the abutment-member 19 on the stationary bed 15 during the movement of the carriage 17, causing the presser-member 18 to press the moistened, adhesive tab firmly against the note-sheet to secure it thereto. 40 It will be noted that a single swinging movement of the movable jaw 17 causes the title and other desired indicia to be printed and the tab to be pressed in place and secured. Suitable, spring-pressed inking rollers 20 are 45 caused to move across the face of the type-block 16 on each actuation of the movable jaw 17, these rollers being carried by a pivoted arm 21 and moving upwardly, from the position shown in Fig. 1, across the face 50 of the type-block 16, and thence upwardly, over the inking plate 22, to receive a fresh supply of ink. The inking rollers 20 are moved up when the printing and pressing operations take place, out of the way of the 55 movable jaw 17. A suitable operating handle 23 is provided, the actuation of which causes the movement of the pivoted jaw 17 and also the movement of the inking rollers 20. The type-block 16 and the abutment-member 19 may be detachably mounted in 60

any suitable manner in a holder or frame-member 24, which can be secured in any suitable manner to the stationary bed 15.

A trough-like rest 25 may be secured to the movable jaw 17 for supporting the 70 music-spool 26 (Fig. 3). This rest may be of such a length that its ends will engage the flanges 27 of the music-spool to properly position the music-spool and the front end of the note-sheet, and may be secured to the 75 movable jaw by means of a pair of bent metal straps 28.

For positioning the V-shaped front end 29 of the note-sheet, a pair of inclined guides 30 are provided, these guides being secured 80 to the movable jaw 17 at such an angle to each other that the edges of end 29 will engage the guides 30, as shown in Fig. 3. These guides 30 also serve to position the tab with respect to the note-sheet, by engaging the edges of the V-shaped front part of 85 the triangular portion 10 of the tab.

For holding the front end 29 of the note-sheet in position, after it has been properly positioned against the guides, a pair of pivoted, spring-pressed arms 31 are provided, having bearing-pads 32 which bear 90 against the note-sheet 13. The pivoted arms 31 are both secured to a rock-shaft 33, which rocks in bearings 34 secured to the carriage 17. For holding the bearing-pads down on the note-sheet, a coil-tension-spring 35 is provided (Fig. 1), which has one end connected at 36 to the base 37 of the machine and has its other end connected at 38 to a 100 rock-arm 39, which is secured at 40 to the rock-shaft 33. In order to facilitate the lifting of the bearing-pads 32, the rock-arm 39 is provided with a rearward extension 41, so that, by bearing down on this rearward extension 41, the bearing-pads 32 can be 105 raised to facilitate the insertion and removal of the note-sheet. This rock-shaft 33, to which the arms 31 and the rock-arm 39 are secured, also provides a pivot for the 110 pivoted presser-member 18 which engages the tab, the presser-member 18 being provided with a pair of arms 42 which are pivotally mounted on the rock-shaft 33, as indicated in Fig. 3.

For normally holding the presser-member 18 in raised position (as shown in Fig. 2,) a coil-spring 43 is provided, one end of which is secured at 44 to the rock-shaft 33 and the other end 45 of which engages 120 underneath one of the arms 42 to normally hold the presser-member 18 in the raised position shown in Fig. 2, out of engagement with the tab.

In using the machine, the operator takes 125 the music-roll 26, places it in position in the rest 25 (as shown in Fig. 3,) draws out the front end 29 of the note-sheet, presses down on the extension 41 to raise the arms 31, slips the front end of the note-sheet 130

under the raised bearing-pads 32, positions the front edges of the note-sheet against the guides 30, and then releases the extension 41 to let the bearing-pads 32 press down on the note-sheet under the influence of the spring 35. The operator then takes one of the tabs, moistens the adhesive, slips the annular portion 11 through one of the metal rings 14, doubles the tongue-portion 12 back on itself, bringing the parts of the tab to the position shown in Fig. 6, and places the tab in position with respect to the front end of the note-sheet, with the moistened, adhesive face of the triangular portion 10 of the tab in engagement with the note-sheet, the front edges of the triangular portion 10 being brought up against the guides 30 to insure the proper relative position of the tab and the note-sheet. The operator then presses down on the handle 23, which swings the movable jaw 17 upwardly, to the position shown in dotted lines in Fig. 2. This brings the note-sheet 13 against the type-block 16, causing the title and other desired indicia to be printed, and also brings the pivoted presser-member 18 against the abutment-member 19, causing the presser-member 18 to swing relatively to the carriage 17 (by holding the presser-member 18 from movement, thereby resulting in the carriage 17 moving up against it) to cause the presser-member 18 to bear on the tab to press the tab firmly against the note-sheet to cause it to adhere thereto.

3. In the claims where the expression "attaching tab" is used, it is to be understood as meaning a tab by which the front or leader end of the note-sheet may be attached to the take-up roll of an automatic musical instrument.

Having thus described my invention, what I claim as new and desire to secure by Letters Patent of the United States is:

1. A machine comprising means for impressing a character on a note-sheet for an automatic musical instrument and means for securing an attaching tab to the note-sheet.

2. A machine comprising means for impressing a character on a note-sheet for an automatic musical instrument and means for simultaneously securing an attaching tab to the note-sheet.

3. A machine comprising means for positioning the front end of a note-sheet for an automatic musical instrument, means for positioning an attaching tab with respect to the front end of the note-sheet, means for pressing the tab and the front end of the note-sheet together to cause the tab to adhere thereto, and means for impressing a character on the note-sheet.

4. A machine comprising means for securing a tab having a V-shaped front to a note-sheet having a V-shaped front; said means

comprising a V-shaped guide, against which both of the V-shaped fronts are positioned, and means for pressing the tab and the note-sheet together to cause the tab to adhere to the note-sheet.

5. A machine comprising stationary impression-means, a stationary stop, a carriage for supporting a note-sheet and for supporting a tab in position to be secured to the note-sheet, and a movable presser-member, which, when actuated, presses the tab against the note-sheet; said carriage being movable to bring the note-sheet against said stationary impression-means and to bring said presser-member against said stationary stop to cause said presser-member to press the tab and the note-sheet together. 70

6. A machine comprising stationary impression-means, a stationary stop, a carriage for supporting a note-sheet and for supporting a tab in position to be secured to the note-sheet, and a movable presser-member, which, when actuated, presses the tab against the note-sheet; said carriage being movable to bring the note-sheet against said stationary impression-means and to bring said presser-member against said stationary stop to cause said presser-member to press the tab and the note-sheet together; said presser member being mounted on said carriage. 80

7. A machine comprising stationary impression-means, a stationary stop, a carriage for supporting a note-sheet and for supporting a tab in position to be secured to the note-sheet, and a movable presser-member, which, when actuated, presses the tab against the note-sheet; said carriage being movable to bring the note-sheet against said stationary impression-means and to bring said presser-member against said stationary stop to cause said presser-member to press the tab and the note-sheet together; said presser member being pivotally mounted on said carriage. 95

8. A machine comprising stationary impression-means, a movable carriage for supporting a note-sheet and a tab in proper position with respect to each other, and means whereby movement of said movable carriage will cause said impression-means to act on the note-sheet and will cause the tab to be secured to the note-sheet. 110

9. A machine comprising stationary impression-means, a movable carriage for supporting a note-sheet and a tab in proper position with respect to each other, and means whereby movement of said movable carriage will cause said impression-means to act on the note-sheet and will cause the tab to be secured to the note-sheet; said carriage being provided with means for supporting the music-spool. 120

10. A machine comprising a movable carriage, means thereupon for supporting a note-sheet and a tab in proper position with 130

respect to each other, means mounted on said carriage for supporting a music-spool, and means whereby movement of said carriage will cause the tab to be secured to the note-sheet.

11. A machine comprising a guide, means for holding a note-sheet for an automatic musical instrument against said guide, means for holding an attaching tab against said guide in position with respect to the note-sheet, and means for effecting the securing of the tab to the note-sheet while thus held.

12. A machine comprising a guide, means for holding a note-sheet for an automatic musical instrument against said guide, means for holding an attaching tab against said guide in position with respect to the note-sheet, and means for pressing the tab and note-sheet together to effect the securing of the tab to the note-sheet.

13. A machine comprising means for holding a note-sheet for an automatic musical instrument, means for holding an attaching tab in position with respect to the end-part of the note-sheet, and means for pressing the tab and note-sheet together to effect the securing of the tab to the note-

sheet; the last said means comprising means for applying pressure to the second said means.

14. A machine comprising means for holding a note-sheet for an automatic musical instrument, means for positioning an attaching tab with respect to the end-part of the note-sheet, means for holding the attaching tab in position against the note-sheet, and means for effecting the securing of the tab to the note-sheet while thus held.

15. A machine comprising means for holding a note-sheet for an automatic musical instrument, means for positioning an attaching tab with respect to the end-part of the note-sheet, means for holding the attaching tab in position against the note-sheet, and means for effecting the securing of the tab to the note-sheet while thus held; said positioning means comprising a V-shaped guide.

In witness whereof, I have hereunto subscribed my name.

JOHN A. FISHER.
